UNITED STATES PATENT OFFICE.

LINCOLN J. CARTER, OF CHICAGO, ILLINOIS.

THEATRICAL SCENERY.

No. 843,583.

Specification of Letters Patent.

Patented Feb. 12, 1907.

Application filed July 28, 1905. Serial No. 271,577.

To all whom it may concern:

Be it known that I, LINCOLN J. CARTER, a citizen of the United States, residing at Chicago, in the county of Cook and State of Illinois, have invented certain new and useful Improvements in Movable Theatrical Scenery, of which the following is a specification.

My invention relates to improvements in theatrical scenery formed of an endless 10 scenic curtain or curtains movably supported in an endless track or tracks and provided with mechanism for driving each of the curtains.

The object of my invention is to provide 15 an endless movable scenic curtain mechanism for theaters with simple, economical, and efficient supporting and driving mechanism.

The invention consists in the features, combinations, and details of construction herein- 20 after described and claimed.

In the accompanying drawings, Figure 1 is a plan view of a suspended scenic curtain driving and supporting mechanism as it ap- 25 pears when constructed in accordance with these improvements; Fig. 2, a detail view of the upper sheet-metal portion of one of the curtains, showing the perforations there- 30 in; Fig. 3, a sectional view taken on line 3 of Fig. 1 looking in the direction of the arrow; Fig. 4, a plan view of one end of a second outer curtain and its supporting- 35 track; Fig. 5, a sectional elevation in detail taken on line 5 of Fig. 4 looking in the direc- 40 tion of the arrow; Fig. 6, a sectional elevation of the mechanism shown in Fig. 4, taken on line 6 of said figure looking in the direc- 45 tion of the arrow; and Fig. 7, a detail elevation of the upper portion of the curtain shown in Figs. 4, 5, and 6.

In a scenic apparatus constructed in accordance with these improvements I prefer to use one or more endless curtains arranged in nests or sets, the construction and arrangement of which will be hereinafter more fully 45 described.

Describing one of the curtains—preferably the inner one—I prefer, and, indeed, intend to make it in an endless form, so as to carry out 50 the desirable features which I have in mind, and in two portions—that is, a composite curtain formed of a lower flexible relatively soft portion *a*, preferably formed of textile fabric on which is imprinted, impressed, or 55 secured in any way images, pictures, or rep-

resentations of any desired object, and an upper endless flexible sheet-metal portion *d*, that forms the supporting and intermediate driving member, all of which will more fully hereinafter appear. These two portions—the lower textile fabric portion and the upper relatively harder or sheet-metal portion—are secured together, as shown in Figs. 2 and 3, in any desired manner, so as to form, for all practical purposes, a continuous curtain, and the upper portion, which also forms an intermediate driving member for the curtain, is provided with a number of perforations *k*, through which the gear mechanism, hereinafter described, is engaged with the curtain 60 to operate or drive the same. To support this curtain in the desired manner, a loop *h* is provided, formed of a series of tubes connected together in a continuous manner and slotted on the under side, as at *e*, and as 65 shown particularly in Fig. 3. The upper end of the sheet-metal portion of the curtain is passed through the slotted tube or track portion and inside thereof and is provided with a series of wheels *b* and *c*, secured thereto in 70 any desired way, so as to bear and roll upon the interior of such slotted tube or track portion, as at *f* and *g*. By this arrangement it will be seen that the curtain may be moved around in any desired path, according to the 75 form of the supporting loop or track *h*. To drive or move this endless curtain in the desired manner, and preferably independent of its supporting trolley-wheels, a sprocket-wheel *l* is provided and secured to and mounted 80 upon a suitable shaft *o* at right angles to the plane of the tube. The teeth *m* of this sprocket-wheel are of such a size and so arranged that they enter perforations in the 85 sheet-metal portion of the belt, so that when the driving-shaft *o* is rotated the belt is 90 driven in the desired way. It will be understood that while I have shown but one of these driving sprocket-wheels, and but one series of perforations in the sheet-metal por- 95 tion of the curtain, that two or more driving sprocket-wheels and two or more series of perforations in the belt may be provided, as circumstances may suggest or necessity render expedient.

To prevent the curtain from sagging at its point of engagement with the driving sprocket-wheel, and to hold it in connection therewith, a guiding-block *r* is provided, which is 100 opposite such point and on the outside of the 105 110

belt. This guiding-block is held in its position by means of a bracket *q*, riveted, as at *s*, to the tubular track and extended upwardly and inwardly so as to engage with the upper portion of the driving-shaft *o* and form a bearing-point therefor. (See Figs. 1 and 3.) The loop or tubular track portion *h* is provided with a plurality of brackets or clip portions *i*, having socket portions *j* at the point of engagement with the track, so that they may be connected to any suitable supporting-framework. (Not shown.)

It will thus be seen that I have provided a continuous composite curtain formed of two parts—a lower textile or soft-fabric portion and an upper relatively harder or sheet-metal portion, which forms substantially a continuous portion thereof, and thus dispenses with the use of chains, links, or similar elements and by which I am enabled to drive the curtain when it is in a comparatively loose condition and without any danger thereto, which might be the case if the upper portion was formed of fabric or an articulated member or members. It is also desirable in some instances to provide one or more extra curtains, so that any of such curtains may be arranged to travel at a rate of speed different from the other, and thus enable objects, mechanism, or actors to occupy the space between the different curtains. In order to do this, a second curtain 2 is mounted outside of and so as to encircle the above-described curtain *a*. This outer curtain is also formed of two parts—a relatively soft fabric portion 2 and an upper inner sheet-metal or relatively harder portion 11, which is secured thereto inside of the upper edge of the soft portion, as shown particularly in Fig. 6. By this arrangement the sheet-metal part is entirely obscured, rendering it comparatively easy to fix any desired object or picture thereto. The sheet-metal part is also provided with a series of perforations 12, adapted to be engaged by the teeth 17 of a second driving sprocket-wheel 16, mounted upon a driving-shaft 18, as shown particularly in Figs. 4 and 5. To prevent this portion of the curtain from sagging, as well as to keep it in operative engagement with the driving sprocket-wheel, a pair of guiding wheels or pulleys 21 are provided and mounted upon a standard or post 19, so as to straddle or span the point where the sheet-metal portion of the curtain engages with the driving sprocket-wheel, as shown particularly in Fig. 5. This standard or post is braced by means of the stay-rods 20, so as to hold it in efficient operative position. To support this second curtain in the desired operative position, a track 3 is provided and arranged in the shape of a loop, part of which only is shown, so as to encircle the inner loop or track *h*, and this track is supported in position by means of a framework formed of an

upright part or parts 5 and a base portion 6, strengthened by means of diagonally-arranged stay-rods 7 and 8. The sheet-metal portion of the curtain is provided with a plurality of grooved trolley wheels or rollers 4, secured thereto in any desired way, so as to straddle the track portion, as shown particularly in Figs. 4, 5, and 6. When desired, a metal reinforcing strap or strap portions 13 may be provided to strengthen the sheet-metal portion of this second curtain at the point where the trolley-wheels are secured thereto—that is, where the trunnions 14 of said trolley-wheels are secured thereto. It will be seen that by this arrangement the sheet-metal portion of this outer curtain extends to and above the supporting trolley and track mechanisms, effectually hiding the same from view, while at the same time affording an efficient supporting and intermediary driving means. Different prime movers may be used to operate these two driving-shafts *o* and 18, or a single prime mover may be connected therewith in any desired manner, (not shown,) so as to drive each of the belts at a speed different from the other when circumstances make it desirable or necessary, all of which will be understood and appreciated by those skilled in the art.

I claim—

1. In an apparatus of the class described, an endless curtain composed of two continuous sheet portions suitably united together, and means engaging one of the portions for driving and operating the curtain. 95
2. In an apparatus of the class described, an endless curtain the body of which is composed of two parts—a lower continuous relatively soft sheet portion and an upper continuous relatively hard sheet portion secured thereto, and means engaging the relatively hard sheet portion for driving and operating the curtain, substantially as described. 105
3. In an apparatus of the class described, an endless sheet-curtain the body of which is formed of a lower relatively soft sheet portion and of an upper relatively hard sheet portion provided with a series of perforations, and gear mechanism engaging the perforations in the sheet-metal portion for driving and operating the curtain, substantially as described. 110
4. In an apparatus of the class described, the combination of a loop or track portion formed of an endless tube slotted on its under side, an endless sheet-curtain the body of which is formed of a lower relatively soft fabric portion and of an upper sheet portion of relatively hard material extending in through the slotted portion of the track and provided with a series of perforations, roller mechanism secured to the sheet-metal portion of the curtain inside the tubular track portion so as to support said curtain, and gear mechanism engaging the perforations in 125
5. In an apparatus of the class described, the combination of a loop or track portion formed of an endless tube slotted on its under side, an endless sheet-curtain the body of which is formed of a lower relatively soft fabric portion and of an upper sheet portion of relatively hard material extending in through the slotted portion of the track and provided with a series of perforations, roller mechanism secured to the sheet-metal portion of the curtain inside the tubular track portion so as to support said curtain, and gear mechanism engaging the perforations in 130

the sheet-metal portion of the curtain for driving and operating the same, substantially as described.

5. In an apparatus of the class described, 5 the combination of an endless curtain the body of which is formed of two parts—a lower relatively soft portion and an upper portion of relatively hard material having perforations therein, means for movably susp- 10 pending said curtain, a toothed sprocket-wheel in engagement with the perforations in the sheet-metal portion of the endless curtain, and guiding mechanism contacting the opposite side of the curtain and adjacent the 15 teeth of said sprocket-wheel to hold the sheet-metal portion of the curtain in operative engagement therewith, substantially as described.

6. In an apparatus of the class described, 20 the combination of an endless composite curtain the body of which is formed of a relatively soft fabric lower portion and of a sheet-metal relatively hard upper portion said upper portion being suitably perforated, means for movably supporting said curtain in position, 25 a sprocket-wheel having its teeth in engagement with the perforations in the sheet-metal portion of the curtain for driving the same, and a pair of guiding wheels or rolls 30 contacting with the side of the curtain opposite the toothed sprocket-wheel and straddling the perforations in the said metal portion of the curtain for holding the same in

operative engagement with the sprocket-wheel, substantially as described.

7. In an apparatus of the class described, 35 the combination of a loop formed of a hollow tubular track portion slitted on its under side, an endless curtain portion formed of a lower relatively soft fabric portion and an upper 40 sheet-metal portion extending in through the slitted portion of the circular track and provided with a series of perforations, a plurality of supporting trolley-wheels secured to the sheet-metal portions inside of the tubular 45 track, sprocket-wheel mechanism having its teeth in engagement with the perforations of the sheet-metal portion of the curtain for driving and operating the same, an outer curtain formed of an upper perforated sheet- 50 metal portion, an outer depending continuous portion formed of relatively softer fabric forming the face portion of such curtain, a track arranged inside of and below the upper edge of the sheet-metal portion of said curtain, trolley-wheels secured to the inner side 55 of said sheet-metal portion and resting upon said track, and a toothed sprocket-wheel engaging the perforations of the sheet-metal portion for driving and operating the curtain, 60 substantially as described.

LINCOLN J. CARTER.
